UNITED STATES PATENT OFFICE.

WILLIAM McCORMICK, OF BROOKLYN, NEW YORK.

ASH-SIFTER.

1,260,222.

Specification of Letters Patent. Patented Mar. 19, 1918.

Application filed March 2, 1917. Serial No. 152,110.

To all whom it may concern:

Be it known that I, WILLIAM McCORMICK, a citizen of the United States, residing at Brooklyn, in the county of Kings and State 5 of New York, have invented new and useful Improvements in Ash-Sifters, of which the following is a specification.

The present invention relates to improvements in ash sifters.

10 In carrying out my invention it is my purpose to produce a device of this character wherein the cinders may be easily and quickly separated from the ashes, the said cinders being retained in a suitable compartment separable from the ashes, whereby either the ashes or the cinders may be independently removed, the construction being such as to prevent the escape of dust during the sifting operation.

20 It is a further object of the invention to produce an ash sifting apparatus which shall be of a simple construction, cheap to manufacture, easily operated and which will accurately perform the functions for which 25 it is devised.

With the above and other objects in view the improvement resides in the construction, combination and arrangement of parts set forth in the following specification and falling within the scope of the appended claims.

In the drawings:

Figure 1 is a perspective view of an ash sifting apparatus constructed in accordance with the present invention,

35 Fig. 2 is a vertical longitudinal sectional view through the same,

Fig. 3 is a transverse sectional view approximately on the line 3—3 of Fig. 2,

40 Fig. 4 is a transverse sectional view approximately on the line 4—4 of Fig. 2,

Fig. 5 is a horizontal sectional view approximately on the line 5—5 of Fig. 2,

45 Fig. 6 is a top plan view of the casing of the device, the closure being in its open position and the sifting member being removed,

Fig. 7 is a perspective view of the reciprocating member or slide, and

Fig. 8 is a perspective view of the sifter.

Referring now to the drawings in detail, 50 the numeral 1 designates a suitable receptacle which, in the present instance, is box-shaped and has an open top provided with a hinged closure 2. Upon the inner face of the closure are provided depending elements 55 3 providing breaker or agitator members

which contact with the ashes arranged in the receptacle, in a manner presently to be described and so tend to separate the ashes from the cinders.

The box-like receptacle 1 upon one of the faces thereof and adjacent the bottom is formed with a substantially rectangular opening within which is arranged a removable drawer 4, serving as an ash receiving element or pit and the outer face of the 65 said drawer is projected beyond all of the edges of the drawer proper so as to fully close the opening in the receptacle and prevent the passage of dust through the opening when the drawer is in its closed position. The drawer is, of course, provided with the usual handle whereby to facilitate the sliding thereof.

The receptacle 1 at the upper portion or mouth thereof is provided with inwardly 75 and downwardly inclined members 5 and below the said members is provided with longitudinally extending cleats forming ways 7—7 for a reciprocating member herein-after to be described. The hopper-shaped 80 mouth of the receptacle is adapted to receive the hopper-shaped body 8 of the sifter member, the bottom of which is reticulated, as indicated by the numeral 9, and the said body, at the sides thereof, is provided with 85 downwardly projecting studs 10—10. The hopper 8 at the sides thereof is provided with revoluble catch members 11 arranged in suitable bearings 12, and each including a rod-shaped jaw having its upper portion 90 offset, as at 13, and received in the slot in the cut away portion 14 of the bearings. The outer ends of the rods are provided with offset handles 15 and the lower ends of the rods being provided with offsets forming 95 a hook member 16. By this arrangement it will be noted that when the central offset portion contacts with the end wall provided by the opening in the bearing 12, the hook-shaped members will be turned 100 angularly or downwardly with respect to the hopper, but when the rods are turned so that the handles are arranged against the side walls of the hopper, the said hooks are disposed below the reticulated face of the 105 hopper. If desired the reticulated face of the hopper may be provided with transverse reinforcements.

Mounted for rectilinear movement in the ways 7—7 is a frame 16', preferably compris- 110

ing spaced side and end members. The end members are each provided with transversely arranged elongated slots or openings 17—17 adapted to receive the projecting studs 10 upon the sifter member 8, and when the catch members are actuated to bring their hooks into contacting position with the transverse or end members of the slide, it will be noted that the sifter member or hopper is locked to the slide. It is, of course, to be understood that the sifter member is of a size sufficient to permit of a desired longitudinal movement thereof in the mouth of the box-like casing 1.

15 Connected with the reciprocatory member or slide at one end thereof, is a pitman 20 that has its free end connected with the crank portion 21 of a shaft 22, the said shaft being journaled in suitable bearings 23 and 24 in the receptacle. To one end of the shaft 21 is secured a pinion 23 which intermeshes with a similar pinion 24 arranged upon a shaft 25 that is journaled in suitable bearings secured upon the inner face of the receptacle and which shaft 25 projects through a suitable opening in one of the sides of the receptacle, the said projecting end of the said shaft being provided with an operating handle 26. By turning the shaft 25 it will 30 be noted that the intermeshing gears will revolve the shaft 21, oscillating the pitman 20 which being connected with the slide imparts a rectilinear movement thereto. The sifter member, it will be noted, may be 35 readily disassociated from the slide by operating the catch members so that the handles thereof are turned inwardly of the hopper for the sifter and these handles then pro-

vide means whereby the hopper may be raised out of the mouth of the receptacle. 40 The cover 2 is of course brought to closed position when the device is operated to separate the ashes from the cinders, and if desired, the intermeshing wheels heretofore referred to as well as the shafts therefor may 45 be arranged in a separate compartment so that danger of the dust from the sifted ashes contacting therewith will be prevented.

Having thus described the invention, what I claim is:

1. An ash sifter comprising a receptacle, guides secured therein, a frame slideable on said guides, a hopper disposed upon said frame and having a reticulated bottom, studs on the bottom of said hopper at its corners engaging within slots in said frame, and means for reciprocating said frame.

2. An ash sifter comprising a receptacle, guide cleats secured therein, a frame slideable on said guides, a hopper having a reticulated bottom disposed upon said frame, brackets secured upon the end walls of said hopper, rods journaled through said brackets and prevented from longitudinal movement therein, offsets on said rods engageable with the end walls for limiting the rotation of said rods, hooks on the lower ends of said rods engageable with said frame, means for reciprocating said frame, and angular extensions on the upper ends of said 70 rods serving as handles for turning said rods serving as handles for their operative and inoperative positions and further serving as handles for removing said hopper.

In testimony whereof I affix my signature.

WILLIAM McCORMICK.

Copies of this patent may be obtained for five cents each, by addressing the "Commissioner of Patents, Washington, D. C."
